UNITED STATES PATENT OFFICE.

ROBERT F. RASMUSSEN, OF OSHKOSH, WISCONSIN, ASSIGNOR TO C. A. LIBBEY COMPANY, OF OSHKOSH, WISCONSIN, A CORPORATION OF WISCONSIN.

LOWER-STANCHION-SECURING MEANS.

Application filed December 26, 1919. Serial No. 347,276.

To all whom it may concern:

Be it known that I, ROBERT F. RASMUSSEN, a citizen of the United States, and resident of Oshkosh, in the county of Winnebago and State of Wisconsin, have invented new and useful Improvements in Lower-Stanchion-Securing Means, of which the following is a description, reference being had to the accompanying drawings, which are a part of this specification.

The present invention relates to certain new and useful improvements in stall appliances and refers more particularly to a lower stanchion connecting member adapted to be set in the usual concrete curbing when the same is poured.

One object of this invention is to provide a lower stanchion connecting member adapted to be set in the concrete curbing when the same is poured, and which is capable of ready removal from the curbing after the same has hardened.

A further object of this invention is to provide a lower stanchion connecting member of the class described in which the stanchion is readily removably secured thereto by suitable link or other flexible means.

A still further object of this invention is to provide a lower stanchion connecting member so constructed that the same may be placed in the mold form of a concrete curbing so that the curbing may be poured to secure the same firmly therein when it becomes hardened, and at the same time permit its ready detachment therefrom.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings I have illustrated one complete example of the physical embodiment of my invention, constructed according to the best mode I have so far devised for the practical application of the principles thereof, and in which:

Figure 1 is a front view of the lower portion of a stanchion and a portion of a concrete curbing having my invention embodied therein, parts being broken away and in sec-

tion to more clearly illustrate the details of construction.

Figure 2 is a transverse sectional view through the lower stanchion connecting member, the said view being taken on the line 2—2 of Figure 1.

Figure 3 is a view similar to Figure 1 depicting a slightly modified manner of employing my lower stanchion connecting member in connection with a stanchion, and

Figure 4 is a transverse sectional view through the form of lower stanchion connecting member depicted in Figure 3, said view being taken on the line 4—4 of Figure 3.

Referring now more particularly to the accompanying drawing, 5 designates a stanchion, 6 the stall concrete curbing, and 7 a flexible chain connecting the lower end of the stanchion to the curbing 5 as more clearly hereinafter described.

The lower stanchion connecting member comprises two complementary angular bracket members 8, each formed with a top transverse portion 9 and a depending side portion 10. The side portions 10 have formed centrally therein a sunken recess 11 which is centrally apertured to receive a fastening bolt 12 which is passed transversely through the curbing 6 to retain the members 8 thereon. The recesses 11 are of sufficient depth to completely cover the head 13 and 14 of the bolt 12 for convenience in inserting the members 8 between the usual longitudinally extending mold form members, not shown, employed in constructing the curbing 6. The side portions 10 have also formed on their inner faces adjacent their lower ends a pair of inwardly projecting lugs or bars 15 which bite into the side walls of the curbing 6 and with the rear wall of the recesses 11 assist in retaining the members 8 in position in the curbing 6.

The top surfaces of the members 8 are bifurcated or slotted as at 16, and each have depending therefrom near their side edges a pair of transverse ribs 17. The concrete when poured to form the curbing 6 surrounds the ribs 17, bars 15 and the rear wall of recesses 11 and engages between the recesses formed by the bifurcated top of each member 18 to thus securely clamp the same upon the curbing 6 against lateral movement.

Projecting upwardly from the corner of

each member 8 is a lug or ear 18 which is centrally apertured to receive a transverse bolt 19 which passes through one end of the chain 7 and in the form of my invention 5 depicted in Figures 1 and 2, I employ a pair of sleeves 20 for retaining the chain 7 centrally on the bolt 19.

In Figure 1, I have illustrated two of my 10 lower stanchion connecting members employed with a single stanchion, and when two are employed, the sleeves 20 are used as hereinbefore described, but when one of my lower stanchion connecting members is employed in connection with a stanchion, the 15 sleeves 20 are preferably dispensed with.

What I claim as my invention is:

1. A stall appliance comprising separate bracket members adapted to embrace a curbing, an upwardly projecting ear carried by 20 each bracket member, and a transversely extending bolt extending through and connecting the ears of the bracket members and said bracket members with a stall appliance.
- 25 2. A stall appliance comprising a pair of complementary angular bracket members having ribs which extend downwardly into the stall curbing, means adjustably connecting the bracket members and passing through the stall curbing to removably secure said members thereto, inwardly extending projections formed on the inner faces of the bracket members for biting into the adjacent portions of the curbing, and means

for connecting a stall fixture with the 35 bracket members.

3. A stall appliance of the class described comprising a pair of complementary angular bracket members, means connecting the bracket members and securing the same to 40 a stall curbing, inwardly extending projections formed on the inner faces of the bracket members for biting into the adjacent portions of the curbing, an upwardly projecting ear formed on each bracket member, and a transverse member connecting the ears of the bracket members and the bracket members with a stanchion.

4. A stall appliance of the class described comprising two complementary angular 50 bracket members each having a sunken recess in their depending portion, a locking bolt passed through the depending portions of the bracket members centrally of the sunken recesses therein to secure the bracket members to a stall curbing, the ends of the bolt being disposed within the sunken recesses, projections on the inner faces of the bracket members for biting into the adjacent portions of the curbing, upwardly extending ears formed on the top portions of the bracket members, a bolt connecting the upwardly extending ears, and flexible means connecting said bolt with a stanchion.

In testimony whereof, I affix my signature.

ROBERT F. RASMUSSEN.
